NEWTON K. BOWMAN, OF NORTH LAWRENCE, OHIO.

BONDING PLUG.

Application filed September 6, 1919. Serial No. 322,158.

To all whom it may concern:

Be it known that I, NEWTON K. BOWMAN, citizen of the United States, residing at North Lawrence, in the county of Stark and State of Ohio, have invented certain new and useful Improvements in Bonding Plugs, of which the following is a specification.

This invention relates to an improved 10 plug particularly designed for use in bonding the joints of track rails and has as one of its principal objects to provide a device of this character whereby worn-out or discarded electrical cable may be employed as 15 a bonding conductor.

The invention has as a further object to provide a plug so constructed that a length of cable may be readily connected thereto and wherein the cable will be effectually gripped 20 to provide an efficient electrical connection between the cable and the plug.

A further object of the invention is to provide a plug having gripping wings and wherein these wings may be bent about a 25 cable end in overlapping relation for compressing the wires on the cable into practically an integral mass tightly gripped by the wings for thus not only forming an effectual electrical connection between the 30 cable and the plug but also providing a secure joint therebetween.

And the invention has as a still further object to provide a plug which may be readily secured upon a rail web.

35 Other and incidental objects will appear hereinafter.

In the drawings:

Figure 1 is a perspective view showing my improved plug in detail,

40 Figure 2 is a sectional view taken medially through the plug,

Figure 3 is a horizontal sectional view taken on the line 3—3 of Figure 4 and showing a conventional cable connected to the 45 plug,

Figure 4 is a sectional view taken at substantially right angles to Figure 3 on the line 4—4 of Figure 3,

Figure 5 is a detail perspective view showing a slightly modified form of plug, and

50 Figure 6 is a sectional view showing a conventional cable connected to the modified form of plug,

Fig. 7 is a view showing the coaction 55 of the gripping wings.

In carrying the invention into effect, my

improved plug is formed with a preferably cylindrical shank 10 at one end of which is provided an overhanging head 11 while, at its opposite end, the shank is cored out axially or cupped as shown at 12. As will be noted, the plug is thus preferably formed as an integral structure and may be constructed of any approved material. However, in view of the function of the plug, it 60 will preferably be formed of brass. The head 11 is oblong at its base and rising from the end portions of the head are spaced gripping wings 13 between which, at the base of the wings, is formed a semi-cylindrical or concave channel 14. The outer side walls of the wings converge upwardly toward each other while the inner side walls of the wings are substantially 70 parallel. Thus, the wings are gradually 75 tapered in thickness toward their free ends and, at their outer terminals are feathered or beveled, both in the same direction as shown in Figure 5.

In order that the structural advantages of 80 my improved plug may be accurately understood, I have, in the drawings, shown the device in use. As previously intimated, the plug of the present invention is particularly designed for rendering it feasible to employ 85 worn-out or discarded electrical cable in bonding track rails. In the drawings, I have conventionally shown a portion of such a cable at 15 while the web of an ordinary track rail is indicated at 16, this web being 90 provided adjacent each end, as is usual, with one or more openings therethrough. A piece 95 of cable of a length to extend between meeting rails at the joint thereof is first procured. The length of cable is then connected at each end thereof to one of my improved plugs when the plugs are, in turn, secured to the rail webs. In the interests of clarity I shall now proceed to describe the manner in which the adjacent end of the cable 15 100 is connected to the plug shown as well as the manner in which this plug is secured upon the rail web 16. Initially, the wires of the cable at the adjacent end thereof are bared when the cable wires are laid in the 105 channel 14 of the plug between the wings 13. The free end portion of one of the wings is then curved inwardly over the cable so that the end portion of said wing at its outer side contacts with the inner side 110 of the other wing adjacent its base. The other wing is then bent inwardly over the

first wing so that the straight inner wall of the latter wing contacts with the sloping outer wall of the first wing. The wings will thus coact to form a loop about the 5 cable and by hammering upon the free end portions of the wings, the bending operation thereof may be continued for tightly binding the wings about the cable and contracting the loop formed by said wings. In 10 this connection, it is to be observed that the sloping wall of the innermost wing will coact with the straight wall of the outermost wing in such manner that the free end portion of the innermost wing will be directed 15 inwardly toward the base of the outer wing so that the bending of the wings may be accomplished without difficulty and since the wings are feathered at their ends smooth joints will be provided between the wings 20 at the respective ends thereof. Inward bending of the wings, in the manner just indicated, may, as will be seen, be continued until the wires of the cable are, as shown 25 in Figure 3, compressed practically into a solid mass. A substantially perfect electrical connection will thus be formed between the cable and the plug while, owing to the extreme gripping action of the wings of the 30 plug upon the cable, the cable will be effectually connected to the plug. After the cable has been thus secured to the plug, the shank 10 thereof may, as shown in Figures 3 and 4, be inserted through one of the openings 35 in the adjacent end of the rail web when, by pounding upon the rim of the shank cup, the shank may be overturned against the web for securely connecting the plug with the rail. For this purpose a center punch is preferably used and by hammering there- 40 on the shank will be expanded, so as to fit tightly in the hole provided in the rail web, filling all pores and producing a perfect electric connection, and safeguarding against the entering of corrosive producing ele- 45 ments. It will accordingly be seen that I provide a plug making it readily possible to employ worn out or discarded electrical cable as a bonding conductor since the plug will securely grip the conductor to have 50 entirely adequate electrical connection therewith while the plug may also be readily connected to a track rail.

In Figures 5 and 6 of the drawings, I have 55 illustrated a slight modification of the invention. In this modification, the head 17 of the plug is first formed solid when a

transverse opening 18 is then formed through the head. The head is then split at its outer side to form coacting gripping wings 19 corresponding to the gripping 60 wings 13 of the preferred construction. In this connection it will be observed that the head is rounded at its outer edge while the opening 17 is located eccentrically with respect to the arc of the outer edge of the 65 head so that the wings 19 are thus gradually tapered in thickness toward their free ends. Furthermore, in splitting the head to form the wings, the head is cut through in tangential relation to the opening 18 so that the 70 wings are accordingly feathered at their ends. In some instances it may be preferred to thus form the plug. However, since the modified structure is otherwise identical with the preferred form of the invention and 75 is employed in a similar manner, further description of the modification is believed unnecessary.

Having thus described the invention, what is claimed as new is:

1. A bonding plug including a head and a shank, said head having a pair of wings forming a substantially semi-circular recess between them and tapering outwardly, terminating with substantially parallel bevels, 85 said wings being adapted to fold over a cable placed in said recess and to be pressed around the same, the ends of said wings overlapping each other to completely enfold the cable and form a solid unit therewith, 90 presenting a smooth outer surface.

2. A bonding plug including a head and a shank, said head having a pair of wings forming a substantially semi-circular recess between them and tapering outwardly, 95 terminating with substantially parallel bevels, said wings being adapted to fold over a cable placed in said recess and to be pressed around the same to form a solid unit therewith.

3. A bonding plug including a head and a shank, said head having a pair of wings forming a substantially semi-circular recess between them and tapering outwardly, 105 said wings being adapted to fold over a cable placed in said recess and to be pressed around the same, the ends of said wings overlapping each other to completely enfold the cable to form a solid unit therewith.

In testimony whereof I affix my signature.

NEWTON K. BOWMAN. [L.S.]
